UNITED STATES PATENT OFFICE.

HUGH FRANKLIN HOGAN, OF ALBION, INDIANA.

REFRIGERATOR-CAR.

SPECIFICATION forming part of Letters Patent No. 439,509, dated October 28, 1890.

Application filed March 16, 1887. Renewed August 31, 1888. Again renewed April 10, 1890. Serial No. 347,304. (No model.)

To all whom it may concern:

Be it known that I, HUGH FRANKLIN HOGAN, a citizen of the United States, and a resident of Albion, in the county of Noble and State of Indiana, have invented certain new and useful Improvements in Refrigerator-Cars; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

15 Figure 1. of the drawings is a horizontal section of my refrigerator-car body. Fig. 2 is a side elevation, with outer wall D broken at top and bottom. Fig. 3 is an end view of my car with outer wall S removed. Fig. 4 is 20 a sectional view of my inlet-valve and deflector. Fig. 5 is a view of my water-drip cup. Fig. 6 is a top view of the inner ceiling P. Fig. 7 is a vertical longitudinal section of my car. Fig. 8 is a cross-section of my car. Fig. 25 9 is a detail view of doors and lock. Fig. 10 is a vertical section of my lock.

My invention relates to refrigerator-cars for transporting fresh meats, fish, fruit, and the like; and it consists in the construction 30 and novel combination of parts, as hereinafter set forth.

Referring by letter to the accompanying drawings, A designates a car-body, the sides B of which are each composed of four walls D E F G, which are separated by interposed studs M H to form cold-air spaces I J K. One of the intermediate walls—viz., F—is made of paper-board, and the walls E are lined on their inner faces with paper-board L. The 35 studs H between the outer wall D and the next wall E in the sides of the car-body are alternate studs, and their lower ends rest upon the bottom of the car-body. The upper ends of these studs H do not, however, extend 40 to the top of the car-body, but stop short of the ceiling P of the car-body and form air-passages N between their upper ends and the lower face of the ceiling of the car-body. The studs M alternate with the studs H, and 45 50 their upper ends abut against the ceiling of the car-body, while their lower ends termi-

nate a short distance above the floor Q of the car-body. This arrangement of the studs is applicable to the sides of the car-body, and is employed only between the outer wall D and the wall E next to it. The studs R between the walls E and F G extend from the bottom to the top of said walls, as it is not designed that a draft shall be created in the spaces between said walls, but that said spaces 55 shall be dead-air spaces, which are provided in order that the walls of the car-body may be practically non-conductors of heat and cold. The bottom of the car-body is also constructed with double walls to form a dead-air 60 space, which latter space, however, is not connected with either of the other spaces mentioned. At each end the car-body is provided with four walls S T Y Z, the inner wall Z being cut away at U in its upper corners to 65 make provision for communication with the 70 passages between the walls D E. Studs W are interposed between the end edges of the end walls S T, said studs W extending from the floor-line up to the cut-away points U. 75

The intermediate studs 1 2 3 4 between the end walls S T extend above the ceiling of the car-body. On their inner faces along their upper edges the outer end walls T are provided with transverse timbers 5, which abut 80 against the ends of interposed horizontal longitudinal side timbers 6, the outer edges of said side timbers 6 being in the same vertical planes as the edges of the ceiling P.

Between both ends of the side timbers 6 85 angular deflecting-pieces 7 7 are interposed, ventilating-spaces 8 being left between them, said spaces 8 communicating with the vertical flues or air-spaces 9 between the vertical studs of the end walls of the car-body. The vertical flues 10 between the vertical flues 9 90 communicate with the air-space 11 between the ceiling P and the roof 12 of the car-body, while the vertical flues 9 9 communicate with the tortuous air-spaces in the side walls of 95 the car-body. At their lower ends the flues 9 9 and 10 at both ends of the car-body are provided with downwardly-opening hinged valves 13, which are provided with stop rests or supports 14, which cause the valves to act 100 as deflectors to guide the air up into the flues. On its top the roof of the car is provided with

two horizontal longitudinal ventilating-flues 15 and 16, which have communication with the interior of the car-body through vertical pipes 17 18 near the opposite ends of said flues 15 and 16. The vertical pipes 17 18 are provided with revolving hoods 19 and 20, the latter being provided with vanes or sails 21, which turn the hoods 19 so that they will always close the front ends of the horizontal opening in the tops of the ventilating-pipes 17 18, so that the interior of the car may be thoroughly ventilated and all foul air may be carried off.

Near the ends of the car-body I provide ice-boxes 24 and 25, said boxes being built below and connected with the ceiling of the car. Access is had to the ice-boxes through the roof and ceiling. Each ice-box is provided with three vertical removable partitions 27 28 29, which are designed to separate the blocks of ice and prevent them from jarring against each other in the ice-boxes, and thus prevent the blocks of ice from being broken, which would cause the ice to melt too rapidly. Removable covers 30 fit the mouths of the ice-boxes, the upper faces of said covers being flush with the upper face of the ceiling P. The openings 31 and 32 are closed by covers 33 and 34, which, however, do not enter the air-space between the roof and the ceiling. The ice-boxes 24 and 25 are provided with curved water-discharge pipes 35 and 36—one pipe for each ice-box. The upper ends of these pipes 35 and 36 extend down vertically. They then bend and extend along horizontally to the points 37, and then depend vertically to the points 38, where they again bend and extend back under the upper horizontal portion, and again bend downwardly at 39. The lower ends of the pipes project into water-cups 40, which serve to seal the lower ends of the pipes when the cups are filled or partially filled with water from the melted ice in the ice-boxes. At the upper sides of the bends in the pipes, as at 41 and 42, the pipes 35 and 36 are provided with ventilating-openings 43 and 44, which admit air to said pipes and prevent them from sweating, so that the interior of the car-body is provided with cold dry air. In the sides of the car-body I provide openings 45, which are closed by panes 46 and 47

of glass, having air-spaces between them, and are covered on the outside by removable slides 48, which may be slid back to give the attendant in charge of the car a view of the interior to ascertain the temperature within the car, a thermometer being placed in the car where it can be seen from the window. The interior walls of the top of the car are also lined with paper or paper-board to render this portion of the car practically a non-conductor of heat and cold. The valves at the lower ends of the end flues may be closed in winter to shut off the cold air, thereby making the car a good winter car.

The car-doors 50 and 51 are double doors, hinged to open outwardly. The doors are made hollow to form dead-air spaces within them. The latch or fastening for the doors consists of two slide-bars 52 and 53, the inner ends of which are pivoted between two coincident circular plates 54 55, the outer ends of the slide-bars passing through staples 56 and 57. The coincident plates are pivoted to the outer face of one door, and the outer plate 55 is provided with a short lever 57' for operating the slide-bars to lock and unlock the doors. The meeting edges of the car-doors are beveled, so that the outer door holds the inner one to place when closed.

Having described this invention, what I claim, and desire to secure by Letters Patent, is—

The combination, in a refrigerator-car, of the studs H and the studs M, alternating and forming the tortuous air-passages in the side wall, the flues 9, having the downwardly-opening valves 13, the studs W, cut away at U and connecting the air-passage 9 with the tortuous passage of the side wall, the vertical end flues 10, having the downwardly-opening valves at the bottom of the car, and the air-space 11 between the ceiling and the roof of the car, communicating with the flues 10, substantially as specified.

In testimony whereof I affix my signature in presence of two witnesses.

HUGH FRANKLIN HOGAN.
